UNITED STATES PATENT OFFICE.

HENRY E. CLINTON, OF AUGUSTA, GEORGIA.

HEEL FOR BOOTS AND SHOES.

SPECIFICATION forming part of Letters Patent No. 253,844, dated February 21, 1882.

Application filed December 31, 1881. (No model.)

To all whom it may concern:

Be it known that I, HENRY E. CLINTON, of Augusta, in the county of Richmond and State of Georgia, have invented a new and useful Improvement in Heels for Boots and Shoes; and I do hereby declare that the following is a full, clear, and exact description of the invention, which will enable others skilled in the art to which it appertains to make and use the same, reference being had to the accompanying drawings, which form a part of this specification.

Figure 1 is a perspective view of the heel detached. Fig. 2 is a vertical longitudinal section of the same. Fig. 3 is a vertical longitudinal sectional view, showing the heel attached to a shoe. Fig. 4 is a section on line xx , Fig. 3; and Fig. 5 is a detail view, showing in perspective the plates which constitute my invention.

Corresponding parts in the several figures are denoted by like letters of reference.

This invention relates to an improved method of and means for securing or attaching heels detachably to boots and shoes, in order that they may be easily renewed or interchanged when completely or partly worn, as will be hereinafter fully described, and particularly pointed out in the claim.

In the drawings hereto annexed, A represents a plate, of any suitable metal or other material, which is secured by means of nails, screws, or otherwise to the upper side of a heel, B, upon which it is made to fit nicely, as shown. Plate A is provided on its under side with a centrally-located boss or enlargement, C, having a screw-threaded opening, D. Openings or perforations E E are formed at the front corners (or at some other suitable places) of plate A, which said openings communicate with recesses F in the heel.

G is a plate corresponding in size and shape to plate A, and secured or arranged in the shoe either between the outer and the insole or above the latter. Plate G is provided with downward-projecting prongs H, located to correspond with the location of openings E in plate A. Said prongs pass through openings I in the sole or soles, according to the location of plate G, through openings E in plate A, and into the recesses F in the heel. Plate G is also provided with a central perforation, J, corresponding with the threaded opening D in plate A, and the soles, which are represented by letters K and L, have openings M, corresponding with openings D J in plates A and G.

The heels are attached to the boots or shoes by screws S, inserted from the inside of the soles, as shown. To remove the heels for renewal, or in order to interchange them from one shoe to another, it is only necessary to remove the screws S.

Having thus described my invention, I claim and desire to secure by Letters Patent of the United States—

The combination, with a boot or shoe having a plate, G, arranged upon the inside of the outer sole and provided with perforation J and prongs H, of the heel having a plate, A, secured to its upper side, said plate being provided with a boss, C, countersunk in the heel, and having a threaded opening, D, to receive a fastening-screw, S, and openings E E to admit the prongs H, substantially as set forth.

In testimony that I claim the foregoing as my own I have hereto affixed my signature in presence of two witnesses.

HENRY E. CLINTON.
